UNITED STATES PATENT OFFICE.

SEBA R. WEEKS AND CLARENCE C. BROWN, OF CAMPBELL, CALIFORNIA.

RAIL JOINT.

1,416,144.

Specification of Letters Patent. Patented May 16, 1922.

Application filed February 24, 1922. Serial No. 538,853.

To all whom it may concern:

Be it known that we, SEBA R. WEEKS and CLARENCE C. BROWN, citizens of the United States, residing at Campbell, in the county 5 of Santa Clara and State of California, have invented new and useful Improvements in Rail Joints, of which the following is a specification.

The object of our said invention is the 10 provision of a railway rail joint that renders it unnecessary to employ fish plates and bolts, and is therefore calculated to facilitate the laying of a rail and to lessen the liability of accident.

15 To the attainment of the foregoing, the invention consists in the improvement as hereinafter described and definitely claimed.

In the accompanying drawings, forming part of this specification:—

20 Figure 1 is a side elevation of the joint constituting the best practical embodiment of our invention that we have as yet devised.

Figure 2 is a horizontal section taken in the plane indicated by the line 2—2 of

25 Figure 1.

Figure 3 is a transverse section on the line 3—3 of Figure 1.

Figures 4 and 5 are perspectives of the rail ends comprised in the joint.

30 Figure 6 is a perspective of the joint key.

Similar numerals of reference designate corresponding parts in all of the views of the drawings.

In accordance with our invention one of 35 the rail ends comprised in the joint and which is shown in detail in Figure 4 includes a web 1 and a base 2 extended beyond the major portion 3 of the rail, and an integral lug 4 at one side of the extended web

40 1, the said lug having a beveled forward end 5 and a square rear end 6, Figures 2 and 4. The other rail end of the joint which is shown in detail in Figure 5 includes a thick and comparatively heavy portion 7 at the

45 end of the major portion 6 of the rail. In the said heavy portion 7 are formed a longitudinal socket 8 with a lateral offset or sub-socket 9, and a transverse opening 10 that intersects the said sub-socket 9. At 11

50 in the portion 7 is provided a transverse threaded opening to receive the pivot bolt 12 of a gravitational latch 13, Figures 1—3.

In addition to the elements referred to, the joint comprises a key 14, a bolt 15 and a 55 spring 16; the said bolt 15 being headed and extended loosely through an aperture 17 in

the key 14 and threaded into the rail portion 7, and the spring 16 being mounted on the bolt and interposed between the bolt head and the outer side of the upper portion of the 60 key. At its outer side and adjacent to its lower end the key 14 is provided with a hook 18 for the engagement and support of the latch 13.

In the preferred use of our improvement, 65 the rail end 1 is socketed endwise in the rail portion 7 until the lug 4 passes and is engaged by the inward snapping of the key 14, after which the latch 13 is swung downwardly into the hook 18, Figures 1—3, when 70 outward movement of the key 14 and casual release of the lug 4 will be precluded.

When it is desired to release the lug 4 and the rail end bearing the same, it is simply necessary to raise the latch 13 and move the 75 key 14 outwardly by any appropriate means to permit of the withdrawal of the said rail end.

It will be manifest from the foregoing that our novel joint is at once simple and 80 strong and safe, and this notwithstanding the facility with which the rail ends are joined.

To provide for expansion and contraction in use the socket 8, and sub-socket 9, are 85 made somewhat longer than the lug 4, Figures 1 and 2.

We have entered into a detailed description of the construction and relative arrangement of the parts embraced in the present 90 95 and preferred embodiment of our invention in order to impart a full, clear and exact understanding of the said embodiment. We do not desire, however, to be understood as confining ourselves to the said specific construction and relative arrangement of parts inasmuch as in the future practice of the invention various changes and modifications may be made such as fall within the scope of our invention as defined in our appended 100 claim.

Having described our invention, what we claim and desire to secure by Letters-Patent, is:—

A rail joint comprising two rail ends, one 105 rail end having an extended reduced portion and a lug at one side of said portion, and the other rail end having a socket and a sub-socket to receive said reduced portion and lug and also having a transverse opening 110 intersecting said sub-socket, the said lug having a beveled forward end a square rear end,

in combination with a key in said transverse opening and engaged with said lug, said key having a transverse opening in its upper portion and a hook on the outer side of its lower portion, a headed bolt extending loosely through said opening of the key and connected to the second-named rail end, a spring on the bolt and between the head thereof

and the key, and a gravitational latch pivotally connected to said rail end and seated in said hook.

In testimony whereof, we affix our signatures.

SEBA R. WEEKS.
CLARENCE C. BROWN.
